M. W. TRAVERS ET AL.

PROCESS OF THE MANUFACTURE OF GAS FROM COAL.

Filed March 5, 1923

UNITED STATES PATENT OFFICE.

MORRIS WILLIAM TRAVERS, OF ALDWYCH, LONDON, AND FRANK WILLIAM CLARK, OF LYMM, ENGLAND, ASSIGNORS TO TRAVERS AND CLARK, LIMITED, OF MANCHESTER, ENGLAND.

PROCESS OF THE MANUFACTURE OF GAS FROM COAL.

Application filed March 5, 1923, Serial No. 622,895, and in Great Britain March 9, 1922.

This invention relates to the manufacture of gas by a process which comprises the following two stages:—

In the one stage air is blown into the bottom of the apparatus and coke contained in the lower part or gasification chamber of the apparatus and produced by the carbonization of coal or like material in the upper part or carbonization chamber is thus heated as in the usual procedure during the "blow" period of water gas manufacture, the "blow" gas passing through the coke and out through orifices in the walls of the apparatus between the gasification and carbonization chambers; when the temperature of the coke has been sufficiently raised the air is cut off, and in the other stage steam is admitted to the bottom of the gasification chamber or it may be for short periods to the top of the gasification chamber, and during the "run" the water gas produced in the gasification chamber is allowed to travel through the coal in the carbonization chamber. Such a process yields gas of the nature of city gas and containing only a small proportion of nitrogen and carbon dioxide.

We have found that the available sensible heat of the water gas whether superheated within practical limits of temperature or not is, however, insufficient for the complete carbonization of the coal.

According to this invention and to supply the heat necessary for the complete carbonization of the coal we force some of the gas which leaves the upper part of the carbonization chamber during the run through a regenerator which has been previously heated by the "blow" gas and deliver the gas so heated to the lower part of the carbonization chamber.

Secondary air may be introduced into the regenerator so that the air blow gases may be burnt therein and give up also their latent heat.

Thus the quantity of heat passing into the carbonization chamber during the run is in excess of the quantity available from the gas produced by the action of the steam on the coke during the same period and part of the heat energy of the fuel gasified during the blow is recovered and utilized re-

generatively for the carbonization of the coal.

Our invention is illustrated by the accompanying drawing in which Figures 1 and 2 are vertical sections through two examples of apparatus suitable for carrying out our improved process.

A is the gasification chamber and B is the carbonization chamber, into which coal is fed through a suitable arrangement at C. Beneath the fire bars D are an air inlet E and a steam inlet F. G is a regenerator and at H are orifices through which the air blow gases can pass into the regenerator and the reheated gas returned from the top of the chamber B during the steam run can re-enter the carbonization chamber. At the top of the chamber B is a pipe J through which the gas produced from the coal during the air blow period can escape or be drawn off in determined volume by an exhauster K and delivered through a non-return valve into the outlet main L leading to a gas holder. From the upper part of the carbonization chamber there is also a pipe L' which is connected through a non-return valve to the outlet main leading to a gas holder; pipe L' is provided with a branch pipe M which can be closed by a suitable valve N leading through a fan O to the top of the regenerator G. An opening P provided with a stack valve allows the escape of the waste gases during the blow and secondary air can be admitted to the regenerator as for example through Q.

During the blow period the steam inlet F and the valve N are closed, air is blown in through inlet E and passes up through the coke in the chamber A and through the orifices H into the regenerator where it gives up the major portion of its sensible heat before issuing to waste through outlet P. A supply of secondary air may be delivered through inlet Q so that the air blow gases will be burnt in the regenerator and give up also their latent heat. When the temperature of the coke has been sufficiently raised air inlets Q and E and outlet P are closed and the steam is blown in through inlet F and the valve N is opened and the fan O started. Thus gas issuing from the top of

the chamber B is passed back through pipe M and fan O through the regenerator where it is re-heated and it then issues through orifices H and heats the coal in the chamber B to complete carbonization.

What we claim is:—

1. A process for the manufacture from coal of gas carburetted only by the products of carbonization of the coal, which consists in blowing air during the blow period through hot coke contained in a chamber into which coal is fed at the top, causing the blow gases thus produced to pass through a regenerator without passing through the coal, blowing steam during the run through the coke, passing the water gas thus produced through the coal, and forcing a sufficient quantity of said gas to effect complete carbonization of the coal back through the regenerator and directly through the coal without passing through the main gasification zone.

2. A process for the manufacture from coal of gas carburetted only by the products of carbonization of the coal, which consists in blowing air during the blow period through hot coke contained in a chamber into which coal is fed at the top, causing the blow gases thus produced to pass through a regenerator without passing through the coal, burning the gases in said regenerator, blowing steam during the run through the coke, passing the water gas thus produced through the coal, and forcing a sufficient quantity of said gas to effect complete carbonization of the coal back through the regenerator to the bottom of the carbonization zone and directly through the coal without passing through the main gasification zone.

In testimony that we claim the foregoing as our invention we have signed our names this twenty third day of February, 1923.

MORRIS WILLIAM TRAVERS.
